UNITED STATES PATENT OFFICE.

HELEN PARKER JOHNSTONE, OF GLENRIDGE, NEW JERSEY, ASSIGNOR TO CHENEY BROTHERS, OF SOUTH MANCHESTER, CONNECTICUT, A CORPORATION OF CONNECTICUT.

DESIGN FOR TEXTILE FABRIC.

No. 37,630.

Specification for Design.

Patented Oct. 31, 1905.

Application filed September 22, 1905. Serial No. 279,724. Term of patent 3½ years.

To all whom it may concern:

Be it known that I, HELEN PARKER JOHNSTONE, a citizen of the United States, residing at Glenridge, in Essex county, State of New Jersey, have invented a new, original, and ornamental Design for Textile Fabrics, of which the following is a specification, reference being had to the accompanying drawing, forming a part thereof.

The figure is a plan view of the fabric, showing my new design.

I claim—

The ornamental design for a textile fabric, as shown.

HELEN PARKER JOHNSTONE.
